PAPER DRYING SYSTEM AND APPARATUS
THEREFOR

John W. Bell, St. Catharines, Ontario, Canada

Application September 17, 1937, Serial No. 164,417
In Canada October 6, 1936

3 Claims. (Cl. 34—24)

My invention relates to the drying of webs of paper or the like and more particularly to apparatus and a system whereby economy of heat required for the drying is attained.

5 In the operation of continuous paper mills the sheet of paper formed in and issuing from the wet end of the machine contains about 60 percent moisture. This moisture is removed by passing it over a series of rolls or drums heated 10 by steam above atmospheric pressure whereby the moisture is converted into steam. This steam rises from the paper and mixes with the atmosphere surrounding the paper machine. It is customary to erect hoods over the machine and 15 install fans to withdraw this mixture of air and steam from the machine room. The mixture of air and steam is usually expelled to the outside with a complete loss of the heat units contained 20 in the steam evaporated from the paper. For each pound of dry paper obtained there is evaporated from the paper about 2 pounds of water and to evaporate this water requires from 1½ to 2 pounds of steam delivered to the interior of 25 the drying rolls. The expenditure of this drying steam represents a very material item in the cost of paper production and many schemes have been suggested to make use of the heat units contained in the steam arising from the paper and eliminate this loss. However, regardless of 30 the fact that the paper industry has been actively seeking means to overcome this loss, no system as far as I am aware has found practical acceptance. Systems have been devised and are in practical use for the withdrawal of the mixture of air and steam from the machine room primarily for the purpose of improvement of working conditions therein, but with no material recovery of the heat units.

My invention is directed to a means whereby a large proportion of the heat energy present in the steam coming off the paper web in the drier is recovered and made available for use in the plant. In accordance with my invention I collect the steam liberated from the paper in such a manner that it is free from air and is therefore in a condition whereby the latent heat units contained therein may be utilized in the same manner as any other source of steam.

My invention further contemplates a system whereby the steam driven off from the paper by the drier rolls is collected free from air and used as heating means for the drier rolls. In accordance with my invention I enclose the drier rolls in a chamber which is in communication with the atmosphere through restricted openings

whereby steam liberated from the paper collects in the chamber. I withdraw from the chamber the collected steam at a lesser rate than it is evolved, whereby the steam evolved in excess of 5 the steam withdrawn escapes through the openings and prevents the ingress of air therethrough. Preferably the openings are in the form of slots near the bottom of the casing through which the paper web enters and leaves the chamber and the 10 escaping steam prevents or removes air which tends to be drawn into the chamber by the entering paper web. I withdraw the steam from the chamber at a point remote from the escape openings, compress the withdrawn steam, and 15 deliver the compressed steam as heating medium for the rolls, the heat losses in the system being made up by steam supplied from a boiler supply.

The drawing is a diagrammatic representation of my invention. Reference characters 10 represent a series of drying rolls of the type customarily used in paper machine driers. Each roll consists of a hollow drum mounted for rotation about its axis and connected to driving means. Each roll is provided with means whereby heating steam may be introduced to its interior and condensate removed therefrom. Steam at a 20 pressure above atmospheric is used in the rolls whereby the temperature of the rolls is maintained sufficiently above 212° F. so that the water in the paper may be rapidly evaporated at atmospheric pressure. To keep the drier within practical limits of size, considering the high speed at which paper forming machines operate, it is necessary to raise the temperature of the web rapidly to the boiling point of water and keep 25 it there throughout its travel by supplying a sufficient quantity of heat to make up the latent heat of evaporation. In a practical example, a paper mill operating at a speed of 1,000 feet per minute utilizes rolls of 60 inches diameter offering about 30 320 linear feet of contact with the paper. These rolls are heated by steam at about 8 pounds pressure, having a corresponding condensing temperature of 235 degrees Fahrenheit. This 35 temperature of 235 degrees, maintained in the interior of the roll, is sufficient to overcome the temperature drop of the roll and keep the wet web at the boiling point and supply the latent heat necessary for evaporation. Customarily the heating steam is introduced axially at one end 40 of the roll and condensate removed axially at the other end. Reference character 11 represents a web of wet paper delivered from the "wet" end of the paper making machine (not shown). The web passes about the series of rolls as in- 45 50 55

dicated and leaves the drying rolls at 12 dried to the desired extent.

I provide heat insulated walls 13 completely enclosing the drying rolls and forming a chamber 14 the bottom of which is shown constituted by the floor on which the drier rests. Narrow slots 15 and 16 are provided in the end walls close to the bottom through which the paper web enters and leaves the chamber respectively. 17 10 represents a source of steam supply such as a steam boiler. A pipe 18 leads from the boiler and from the pipe 18 branch pipes 19 lead to each of the rolls. A compressor 20 has its delivery side connected to the pipe 18. The intake of the compressor is connected to a pipe 21 which leads from the pipes 22 communicating with the top of the chamber 14. A pipe 23 delivers steam from the boiler supply 17 to the pipe 21 leading to the compressor as indicated at 24. Valves 25 and 26 in the pipe 18 control the steam supply to rolls from the boiler and the compressor respectively. A control valve 27 is provided in the compressor intake and a regulating valve 28 is provided in the pipe 23.

In preparation for operation the drier in accordance with my invention is brought up to operating temperature by admitting steam from the boiler supply. This may be done by opening valves 25 and 26 and closing valves 27 and 28. 30 The entering steam will raise the temperature of the rolls and the compressor and the temperature of the air within the chamber 14. Valve 28 is then opened which admits steam from the boiler to the top of the casing through pipe 22. 35 The entering steam forces out the air from within the chamber through the slots near the bottom thereof and eventually raises the temperature of the chamber to operating temperature and fills the chamber with steam. 40 To operate the rolls are started and the paper web passes through the chamber in heat transferring relation to the rolls. The web is raised to the boiling point of water quickly and as it continues over the rolls the contained water is 45 converted into steam at 212° F. which escapes into the chamber 14. The compressor is started and valve 25 is closed and valve 27 is opened. Valve 28 is adjusted to admit a limited amount of steam from the boiler. Steam is drawn from 50 the chamber 14 by the compressor which compresses it to the required amount to give the steam temperature required in the rolls, and delivers it to the rolls through the pipes 18 and 19. It is essential that the steam in the chamber 55 drawn off by the compressor be free from air, otherwise the contained air would accumulate in the condensing rolls 10 and stall the system. The steam is collected free from air by preventing the entrance of air through the slots 15 and 16 60 by allowing excess steam to escape therethrough. The valve 28 in the pipe leading from the boiler supply is adjusted to admit sufficient steam so that the compressor draws somewhat less steam from the chamber than is liberated from the 65 drying paper. The excess of steam liberated by the paper escapes through the slots 15 and 16 thus tending to prevent the admission of air at this point. Any small amount of air dragged into the chamber by the incoming paper web is 70 immediately mixed with steam contained in the chamber at the point of entrance. A mixture of steam and air at a given temperature and pressure is heavier than pure steam at the same temperature and pressure, and therefore the air will 75 remain momentarily at the point where it enters

and will be entrained by the outgoing stream of steam and expelled through the slots.

It is particularly to be noted that the steam drawn from the chamber by the compressor is drawn from the top of the chamber at a point remote from the slots, the only point where air can enter the chamber. A plurality of steam outlets 22 are provided to assure that the steam is drawn uniformly from the whole top part of the chamber. Diffusing plates 33 are shown in 10 the chamber opposite the outlets 22. These plates are illustrative of any suitable means which may be employed to assure that the steam is withdrawn uniformly from the top of the chamber avoiding the creation of turbulent currents. 15

As the steam chamber is in communication with the atmosphere through the slots 15 and 16 it will be at atmospheric pressure. Due to the presence of the large mass of rolls and other equipment inside the hood at a temperature 20 somewhat higher than 212° F. the steam will pick up a slight degree of superheat and condensation within the chamber is minimized. Any condensate incidentally formed will collect in the sump at the bottom of the drier and may be drained 25 off in any suitable manner.

The heat losses in the system described are made up by

- (1) Radiation from the housing and accessories. 30
- (2) Heat carried away in the dried paper leaving the drier.
- (3) Heat in the condensate leaving the drying rolls.
- (4) Heat in the steam escaping from the slots 35 15 and 16.

These losses are made up by the steam continuously fed as "make up" through the pipe 23 to the compressor and is regulated in amount by the valve 28. It is obvious that the less steam escaping from the slots 15 and 16, the greater will be the heat economy of the system. In operation the valve 28 will be set to deliver sufficient make up steam so that a sufficient amount of the steam liberated from the paper will escape through the openings 15 and 16 to prevent the ingress of air through these openings and to take care of minor variations in the rate of steam liberated from the paper, due for example to variations in the quantity of water carried into the drier by the web in a given time.

Hoods 29 and 30 are provided over the slots 15 and 16 respectively. Conduits 31 lead from the hoods whereby the steam escaping from the slots 15 and 16 are conducted from the drier room. 55

The following example will illustrate the economy of my system. The heat required, exclusive of radiation and incidental losses, to bring about the required evaporation during the production of 2000 lb. of acceptable finished paper is 60 made up as follows:

	B. t. u.
(I) Heat required to raise 4000 lb. water from room temperature (65° F.) to 212° F. -----	about 588,000 65
(II) Heat required to convert 4000 lb. water at 212° F. to steam at the same temperature -----	about 3,881,600
(III) Heat required to heat the finished paper from room temperature to the temperature at which it leaves the dryer section -----	about 215,000 70

Total ----- 4,684,600

Item (II) constitutes the latent heat of evapo-

ration and represents about 83% of the total heat required. In accordance with my system I return say 98% or more of the steam as heating medium for the rolls in which this latent heat is recovered. Consequently I save about 98% of 83%, or 81% of the total heat necessary to meet the three requirements listed above. The figure of 98% given above for the amount of steam is merely illustrative for purposes of the

10 example representing the case where about 2% of evolved steam is permitted to escape through the slots 15 and 16 for the purpose of excluding air. The amount of steam allowed to escape should of course be as small as possible and will 15 be regulated in practice to as small an amount as is possible to accomplish the results aimed at, i. e. the exclusion of air from the chamber and will vary with the closeness of control exercised and operating conditions.

20 In addition to the above another source of loss is present in systems in which the steam is drawn from the drier room together with air. The scavenging air comes in contact with the heated rolls and other heated parts of the drier and 25 picks up heat therefrom which is lost to the system. This source of loss is eliminated in my system as air is excluded from the chamber surrounding the rolls.

20 The loss of heat in condensate from the interior of the rolls has not been referred to as it is of the same order of magnitude in present systems and in my system. It is moreover in a form which readily leads itself to recovery in heat exchange apparatus.

35 It is evident from the foregoing that I have provided paper drying apparatus whereby a large proportion of the steam given off from the drying paper may be collected free from air and is available for use as a heating medium. It will also be seen that I have invented a system for the drying of continuous web material such as paper wherein a large proportion of the heat necessary to remove the moisture from the paper is reclaimed and used for drying the web. An 45 installation embodying my invention also makes for satisfactory conditions in the drier room as steam is not liberated into the room. As the steam is collected free from air, the loss of heat units in scavenging air present in customary systems is absent.

40 In describing my invention I have diagrammatically shown the principle of operation. It will be apparent to those skilled in the art that ports closed during operation may be provided 55 in the walls of the housing whereby the paper may be cleared in the event of a break in the web during operation.

While I have shown in illustrating my invention a particular manner in which the compressed steam is returned to the drier rolls together with "make-up" steam, it is apparent that modifications of the particular way in which

the compressed evolved steam and the make up steam already under pressure may be returned to the rolls will occur to those skilled in the art. Other modifications within the spirit of my invention will readily occur to those skilled in the art and it is understood that I do not desire to be limited to specific details and steps shown but claim as my invention all modifications which come within the scope of the appended claims.

10 What I claim as new and desire to secure by Letters Patent of the United States, is:

1. The method of drying a web of paper or the like, which comprises passing the web about rolls heated by steam at a pressure above atmospheric and enclosed in a chamber provided with slots through which the web enters and leaves the chamber whereby the steam evolved from the drying web fills the chamber, withdrawing the evolved steam from said chamber at a rate less than it is evolved from said paper and delivered to said chamber, whereby part of the steam escapes through the slots and prevents the entrance of air to the chamber, compressing said withdrawn steam and delivering the compressed steam together with additional steam from another source to the rolls as heating medium therefor.

2. The method of drying a web of paper or the like, which comprises passing the web about rolls heated by steam at a pressure above atmospheric and enclosed in a chamber provided with slots located near the bottom of the chamber and through which the web enters and leaves the chamber whereby the steam evolved from the drying web fills the chamber, withdrawing the evolved steam from the top of said chamber at a rate less than it is evolved from said paper and delivered to said chamber, whereby part of the steam escapes through the slots and prevents the entrance of air to the chamber, compressing said withdrawn steam and delivering the compressed steam together with additional steam from another source to the rolls as heating medium therefor.

3. The method of drying a web of paper or the like, which comprises passing the web about steam heated condensing rolls enclosed in a chamber provided with restricted slots through which the paper passes to and leaves the chamber, supplying steam to said rolls at a pressure above atmospheric pressure by a compressor, admitting steam to the intake of said compressor from said chamber and from another source of steam, regulating the amount of steam admitted from said other source to an amount whereby the compressor draws steam from said chamber at a less rate than it is liberated from the web and delivered to the chamber and whereby excess steam in said chamber escapes through said slots and prevents the entrance of air therethrough.

JOHN W. BELL.
